UNITED STATES PATENT OFFICE.

CHARLES SPAETH, OF CHICAGO, ILLINOIS, ASSIGNOR, BY MESNE ASSIGNMENTS, TO RAYTHEON MANUFACTURING COMPANY, OF CAMBRIDGE, MASSACHUSETTS, A CORPORATION OF DELAWARE.

MEANS FOR ELIMINATING FLUCTUATIONS IN ELECTRIC CURRENT.

Application filed June 7, 1928. Serial No. 114,172.

My invention relates to means for and methods of eliminating objectionable effects of slight voltage or current fluctuations in an electric current.

5 My invention is based on the use of a thermo-couple to bring about the corrective effect. In certain cases one thermo-couple may answer when connected in one side of the circuit and in other cases it may be desired to 10 connect a thermo-couple with each side of the circuit.

My invention has many uses, but for the purpose of this application I will describe it more generally as applied to an electron discharge 15 apparatus. In electron discharge apparatus there is provided a filament which, when heated, throws off electrons to form a path for other circuits associated with said apparatus. Such filament has, in general, been heated by 20 direct current. It is desirable to heat this filament by alternating current because of the elimination thereby of a storage battery in view of the fact that alternating current is used to such a large extent for distributing 25 current.

When electron discharge apparatus of this character is energized by alternating current, it is necessary that one or the other of the 30 circuits associated with the apparatus be in some manner associated with a point in the filament circuit which, at any instant, represents the average potential of the filament circuit. If the filament circuit consists of wire 35 which has absolutely uniform cross section and resistance, then the absolute center point of the filament circuit would be the point of average potential. In general, it is difficult to locate this point exactly and the location of 40 this point when manufacturing devices of this character in commercial quantities is quite difficult, if not impossible. At any rate, this exact location increases the costs to such an extent that it is undesirable to be limited to the discovery of this exact point in 45 manufacturing such devices.

In accordance with my invention, I introduce a thermo-couple into the filament circuit or associate it therewith in any manner which 50 will bring about the result and I then associate the other circuit or auxiliary circuits of the device with the junction point of the thermo-couple.

When two dissimilar metals are joined to-

gether and the junction point is heated and a circuit is established between the terminals 55 of these two elements, then a slight current will traverse this circuit. If now the conditions are reversed and a current is impressed upon the terminals of the thermo-couple, if 60 this current does not exceed the value given out by the thermo-couple when heated, then this current is all consumed at the junction point in producing heat, which heating effect is, of course, entirely aside from the ordinary C²R heating effect. If the current is 65 reversed, the junction point is cooled. Now, if this current fluctuates between zero and the maximum given out by the thermo-couple, the potential of the current is consumed in the heating or cooling effect as the case may be. 70 Thus, if a small alternating current or other variable current whose greatest value would not exceed the value of the current given off by the thermo-couple is passed through the thermo-couple, the heating effect at the junction point would, of course, vary as the current changes its amplitude, but the voltage of the junction point would remain at a constant value.

If then such a thermo-couple be introduced 75 somewhere near the middle point of the filament circuit and the auxiliary circuit or circuits heretofore referred to connected to the junction point, this auxiliary circuit or circuits are then connected to the point of average potential of the filament circuit.

I will explain this more in detail by referring to the accompanying drawing in which—

Fig. 1 shows an electronic discharge tube 80 constructed in accordance with my invention;

Fig. 2 is a diagrammatic illustration of a thermo-couple;

Fig. 3 is a diagram indicating the principles involved; and

Fig. 4 shows my improved electronic device as associated in a radio receiving circuit.

Referring now more particularly to Fig. 1, I show an electronic discharge tube having 100 a base 10 provided with the customary connecting prongs 11, 12, 13 and 14. A stud 15 is also shown for cooperation with the bayonet catch in the socket. An evacuated glass bulb 16 surmounts the base. The tube 105 itself consists of a pair of plate elements 17,

18, a pair of grid elements 19, 20, these being connected together by means of the wire 21 and then connected by means of the wire 22 to one of the connecting prongs. The plates 5 are connected together and are connected by means of the wire 23 with another one of the connecting prongs. There are also two filaments 24 and 25 which are connected by means of the conductors 26 and 27 with the 10 remaining two connecting prongs.

The upper extremities of these filaments are respectively connected to the free ends of the thermo-couple consisting of the steel element 28 and the molybdenum element 29. 15 The free extremity of the free element 29 is connected to the free extremity of the filament 24 and the free extremity of the molybdenum element 29 is connected to the free extremity of the filament element 25. The 20 other extremities of the elements 28 and 29 are soldered or brazed or otherwise suitably fastened together to form a junction point 30 from which junction point a conductor 31 leads outwardly out of the evacuated bulb. 25 16. The thermo-electric couple consisting of the elements 28 and 29 is, of course, preferably associated in the filament circuit so that there is an equal amount of filament in so far as practical constructions can bring it about 30 upon the opposite sides of the thermo-couple. As before stated, this is not always possible of obtainment when commercially manufacturing these devices. If the elements 28, 24 and 26 have exactly the same resistance as the 35 elements 29, 25 and 27, then the junction point 30 would, of course, be at the point of average filament circuit potential. As this, however, is not readily obtainable, the thermo-couple has been introduced so that even 40 though the point 30 is not at the exact point of average potential (eliminating for the moment the effect of the thermo-couple itself), that this point 30 nevertheless will be the point of average potential when taken in 45 connection with the effects of the thermo-couple itself.

To explain this a little more in detail, I have shown in Fig. 2 a thermo-couple consisting of the elements 28 and 29 and having 50 the junction point 30. In Fig. 3 I show a vector diagram in which the line *ab* represents the base line. If we consider the line *cd* as representing one-half of the maximum potential value of the impressed alternating 55 current which we will assume is impressed upon the terminals of the filament circuit, then the line *ef* plus the line *cd* will represent the total maximum pressure. If the line *ce* represents the length of the filament and 60 we take a point midway thereof, such as the point *g*, and draw a line between the points *d* and *f*, it will be seen that the point *g* is at a point of average potential, that is, throughout the entire cycle. We may assume, for 65 the purposes of discussion, that the point *g*

is grounded as at *h*. Thus, if the total impressed pressure is 6 volts, the average potential when the pressure is maximum is 3 volts and the points will always be at this point of average potential throughout the 70 entire alternating cycle. In a similar way the line *ik* represents the potential when the current is flowing in the opposite direction.

Now, in practice, the point to which connection is made is generally a little bit to 75 the right or to the left of the point *g* and for the purpose of illustration, we have chosen the point *l* as representing the junction point 80 30. If then we draw the ordinates *lm* and *ln* to the lines *ik* and *df*, respectively, and project these points over by the lines *o* and *p* and then draw between these lines the sinusoidal curve *q*, we will find that the variation from the point of average potential at the point *l* is represented by the sine curve *q*. 85 In the illustration the amplitude of this curve has, of course, been very much exaggerated, as in practice the variation from the point of average potential would probably be less than 1% of the total impressed pressure. However, the line *g* represents the amount of voltage change from the amount of average potential as represented by the point *g*.

Now if the maximum value as represented 90 by the curve *q* is within the maximum current emission value of the thermo-couple, then the variations due to this curve are consumed in their heating and cooling effect of the junction point so that the junction point 30, instead of being subject to the variations, remains at a constant potential. In other words, the thermo-couple itself within the limits of its own capabilities either absorbs or eliminates or corrects the error due 95 to the selection of the point 30 which occurs 100 in practice. By thus constructing the tube, the point 30 as shown in Fig. 1 is a point which represents the average potential of the filament circuit and if it is grounded, it of course, represents a constant potential. 110 However, the important point is to have one of the other circuits of the discharge tube connected to a point of average filament circuit potential. Under these circumstances, the variations in magnetic or electrostatic 115 effect due to the alternating current in the filament circuit are neutralized in these other circuits so that no objectionable hum is heard should the device be used for radio or similar purposes. The filament itself is, of 120 course, selected in such a way that the lag in its heating and cooling is sufficient to prevent any objectionable influences due to a change in its thermal condition by reasons of 125 the variations in the alternating impressed current.

In Fig. 4 I show my device as applied to a simple detector circuit in which there is the input transformer having the primary 32 and secondary 33, there being also shown 130

a tuning condenser 34 and a grid leak 35. My improved electron discharge device is also shown, as will be readily apparent, the same reference numerals being used as are used in Fig. 1. The filament circuit is shown as being energized from a source of alternating current 36 through the agency of the step-down transformer 37. A "B" battery is shown at 38 and the output terminals are shown at 39, the electronic device in this instance acting as a rectifier. I prefer to use a 9 volt "B" battery in this instance and then associate with the circuit a "C" battery 40 which assists to shift the working position of the tube to its more efficient point on its curve. The "C" battery is preferably about 90 volts and I provide a shunt resistance 41 about this "C" battery which may be all the way from 400 to 2,000 ohms and which is adjustable and which helps to adjust the grid voltage impressed by the "C" battery.

It will be seen that the input circuit of the tube includes the elements 40 and 41 and this input circuit of the tube which includes the grid is directly connected by means of the conductor 31 with the junction point 30 of the thermo-couple which is the point of average filament circuit potential. As the grid circuit is thus connected with a point of average filament circuit potential, the objectionable effects of the alternating heating current are avoided and no hum is heard due to such current. This follows, it is thought, from the descriptive matter which has gone before.

From this description of the circuit arrangement of Fig. 4, it will be readily apparent to those skilled in the art that the device is applicable for use with any number of electron discharge devices. It may

be used in radio receiving sets of any character regardless of the number of such devices. I have in this description, limited myself to describing in detail one form which my invention may take, but I have also stated in the introductory portion of the specification that the principle of the invention is applicable for a great variety of uses and is not limited to the radio art nor to the art of electron discharge devices.

Having, however, thus described one form which my invention may take, what I claim as new and desire to secure by Letters Patent is:

1. An electron discharge device having a casing, a filament circuit therein, and a thermo-electric couple within said casing and associated with said filament circuit adapted to maintain at an average potential a given point of said filament circuit which except for said thermo-electric couple would not represent the point of average potential of said filament circuit.

2. An electron discharge device having a casing, a filament circuit therein, a thermo-couple associated with said filament circuit, and a connection between the junction point of said thermo-couple and the circuit including one of the other elements of said device.

3. An electron discharge device having a casing, a filament circuit therein, a thermo-couple interposed substantially midway of said filament circuit and a connection between the junction point of said thermo-couple and the circuit including one of the other elements of said device.

In witness whereof, I hereunto subscribe my name this 19th day of May A. D., 1926.

CHARLES SPAETH.
